UNITED STATES PATENT OFFICE.

WILLIAM P. WAGNON, OF PORTLAND, OREGON, AND HARRY J. BOMAR, OF TACOMA, WASHINGTON.

FILE-SHARPENING MACHINE.

Application filed October 17, 1921, Serial No. 503,407. Renewed August 21, 1923.

To all whom it may concern:

Be it hereby known that we, WILLIAM P. WAGNON and HARRY J. BOMAR, citizens of the United States and residents, respectively, of Portland, county of Multnomah, and State of Oregon, and Tacoma, county of Pierce, State of Washington, have invented a new and useful File-Sharpening Machine, of which the following is a specification.

This invention relates more particularly to means for resharpening files.

The objects of our invention are to increase the capacity over existing machines, economize abrasives, secure better cutting action from abrasives used, and render the employment of skilled labor less necessary.

We attain these results in the manner set forth in the specification following and illustrated in the accompanying drawing, in which:

Figure 1 is a vertical section through the length of the machine. Figure 2 is a plan of Figure 1 with the guard and a portion of the cover removed. Figure 3 is an end elevation from the operator's side. Figure 4 is a full sized detail of the nozzles.

Similar numbers of reference refer to the same or similar parts throughout the several views.

Referring in detail to the drawing, we have constructed our device of wood and made same in box form having a bottom 10, a top 11, a back 12 and a front 13, as well as the two similar sides 14, all of which are supported by the four legs 15. Inside of the box we have placed a front sloping floor 16 and a rear sloping floor 17 which almost meet in front of the center of the box and form a sump with the bottom of the box. On the upper side of the inclined floor 17 we have placed cleats 18 which form an inverted V almost reaching the sides 14. In front of the center of the cover 11 we have placed an exhaust stack 19. Behind this stack and under the cover 11 is secured an inclined baffle plate 20 on whose rearward or upper side are placed the cleats 21 similar to the cleats 18. Under the stack 19 and secured to the cover 11 is a second inclined baffle 22 upon which are secured the cleats 23. At the forward end of the baffle 22 is secured a curved sheet metal apron 24 whose use will be described later.

A guard 25 rests against the cleats 26

and has an opening 27 sufficiently large to permit the workman to see the operation. A removable cover 27^a occupies the space between the guard 25 and the cover 11.

A steam pipe 28 is mounted in front of 60 the member 13 and has opening upwardly the two T's 29 from which rise the nipples 30 and the elbows 31 which carry the nozzle tips 32, over which are placed the T's 33 whose ends carry the short nipples 34 and 65 whose side openings 35 contain the nipples 36. The elbows 37 on the nipples 36 contain the pipes 38 which reach almost to the bottom of the sump between the lower ends of the floors 16 and 17. 70

Numerous other refinements such as cleaning jets, as are now used on devices of this nature, may be embodied as best seen fit.

In order to prevent an accumulation of 75 water in the sump we have provided an overflow pipe 40 having on its outside a flange 41 and on its inside a gasket 42, a washer 43 and an elbow 44 which is turned upwardly and to the rear, or away from 80 the path of the steam. This prevents steam and abrasives from being blown out of the waste pipe 40.

The operation of our device is as follows: 85 A file 39 is placed between the nozzles 34 and steam is admitted through the pipe 28. A quantity of water and abrasives having been placed in the sump it is a well known fact that the steam will draw the liquid and abrasives up through the pipes 38 and project same with great force against the file in the direction of its point. This steam spends its force in striking the baffle 22, the floor 17 and the baffle 20 by which time it has lost most of its force and abrasives, 90 and the steam now passes out through the exhaust stack 19. Some abrasives and water may also offer to escape through the opening 27 but will be deflected downwardly by the apron 24. 95 100

It will be observed that by putting the cleats on the floor 17 and the baffles 20 and 22 that any abrasive laden steam will be carried by the cleats to the outer sides of the box where the velocity of the steam is 105 much less which will permit the return of the abrasives to the sump instead of expelling same through the stack 19.

Experience has indicated that the money value of the abrasive alone might not in 110

some cases warrant the above-mentioned precautions, but it has also taught us that reusing the abrasive continually improves its action on the file since it forms a kind 5 of mud or cement which materially assists in the process. Were these materials constantly blown away as is now done, leaving only the clean abrasive, the results would be disappointing as far as speed and quality 10 of work are concerned.

By the use of two fine nozzles directed against opposite sides of the work we not only double the capacity of the machine, but lessen the work for the operator, for he does 15 not need to hold the file against the single jet of steam.

It will be understood that numerous devices have been produced purporting to sharpen files by this process, particularly referring to one by Huntley 673,576. We do 20 not therefore claim this device broadly, but only within the limits set forth in the following claims in which our improvements are clearly pointed out.

25 What we claim is:

1. A file sharpening machine consisting of

an elevated box having sump forming inclined floors and a series of baffle plates around which steam must pass before being exhausted, in combination with a pair of converging injectors for carrying material from said sump and projecting same against two sides of a file at the same time, and an overflow pipe having its inlet turned upwardly and rearwardly away from the discharge of the injectors. 30

2. In a file sharpening machine, the combination of a box means, a pair of injectors which converge within said box, two bottoms sloping toward the middle of said box, cleats secured on the upper side of the farthest 35 slope in the form of an inverted V, a discharge stack near the forward end of the top of said box, a downward and rearwardly sloping baffle attached to the under side of the box cover in front of said stack, a pendant apron in front of the upper end of said baffle, and a downwardly and forwardly sloping baffle behind said stack. 40

WILLIAM P. WAGNON,
HARRY J. BOMAR. 45
